UNITED STATES PATENT OFFICE.

NATHAN S. RUDDOCK, OF GRANITE FALLS, MINNESOTA.

WASHING-MACHINE.

SPECIFICATION forming part of Letters Patent No. 393,033, dated November 20, 1888.

Application filed December 17, 1885. Serial No. 185,920. (Model.)

To all whom it may concern:

Be it known that I, NATHAN S. RUDDOCK, a citizen of the United States, residing at Granite Falls, in the county of Yellow Medicine and State of Minnesota, have invented certain new and useful Improvements in Washing-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to washing-machines, and more particularly to that class in which reciprocating pounders are employed.

The invention consists, first, in a novel construction of the pounders, and, second, in a novel means of mounting and operating said pounders. The invention further consists in various features and details of construction hereinafter set forth and claimed.

In the drawings, Figure 1 is a view of my improved machine with the side of the tub or vat removed; Fig. 2, a top plan view; Fig. 3, a perspective view of one of the pounders; Fig. 4, a vertical sectional view of the same; Figs. 5, 6, and 7, horizontal sectional views taken, respectively, on the lines $x-x$, $y-y$, and $z-z$, of Fig. 4; and Figs. 8, 9, and 10, views illustrating the construction of the blocks or clamp by which the pounders are attached to the operating-shaft.

35 I desire to state that I am aware that it is not new to provide a washing-machine with reciprocating pounders so constructed as to force air into the water and among the clothes; and hence I make no broad claim thereto.

40 My machine I believe possesses advantages over those heretofore employed, and is found in practice to operate efficiently.

Referring again to the drawings, A indicates a tub or vat divided by means of an upright partition into a cleansing-compartment, B, and a rinsing-compartment, C, as shown in Figs. 1 and 2, the said compartments being each provided with spigots by which the water may be withdrawn. Cleats a' are secured to the end walls of compartment B, as shown in Figs. 1 and 2, for a purpose presently to be explained, said cleats having their lower (and

preferably also their upper) faces beveled or inclined toward the walls of the compartment in which they are situated. In the drawings 55 I have shown four of these cleats a' ; but it is obvious that one cleat on each end wall, extending entirely across the compartment, may obviously be substituted, if desired.

D indicates a shaft supported at its ends in 60 bearings a upon the sides of the tub and extending centrally across the compartment B, as shown in Figs. 1 and 2, said shaft being provided with cranks b and b' , diametrically opposite to each other. At one end the shaft 65 is provided with a small gear-wheel, E, which meshes with a larger gear, F, mounted upon the tub or upon an arm or bracket secured thereto. This large wheel F is provided with a handle c , as shown in Fig. 2, by which it may 70 be turned.

G G indicate the pounders, hereinafter fully described, which are mounted upon or attached to the cranks b b' by means of blocks H. (Shown in Figs. 8, 9, and 10.) These 75 blocks comprise three parts, d , e , and f , which are secured together by means of bolts g , extending through them, as shown, and when they are thus secured together they form an efficient connecting device for the shaft and 80 pounders. The parts d e have in their adjacent faces a horizontal semicircular groove, and the parts e f at their line of meeting each have a vertical groove, as clearly shown in Fig. 8, these grooves forming a bearing, h , for 85 the shaft and an opening or socket, i , for the pounder. When the parts are applied to the shaft and the pounder, as illustrated in Figs. 9 and 10, and the bolts g inserted in place, it will be seen that the pounder is not only secured rigidly within the block, but that the latter, while prevented from becoming detached from the shaft, is capable of swinging or oscillating thereon. By means of the bolts 90 g the parts d and e may be made to bind upon 95 the shaft with more or less force, and thus compensate for wear.

Referring now to Figs. 3 to 7, inclusive, the construction of the pounders will be particularly described. These pounders comprise a 100 main body, j , (preferably cylindrical,) provided with a conical mouth, k , and a cap, l . For convenience, the upper end of the body j will be formed with a screw-thread, upon

which the cap *l* screws, as shown in Figs. 3 and 4; but it is obvious that any other means may be employed for retaining the cap in place. Cap *l* is provided with air inlet or opening *m*, and against its under face rests a disk or valve, *n*, carried at the upper end of a spiral spring, *o*, as shown in Fig. 4, said spring being supported by a narrow cross-bar, *p*, which permits air to pass upon either side into the main body. Upon opposite sides of the main body *j* are vertical ducts or passages *q*, which communicate at their upper ends with the interior of the pounder, as shown in Fig. 4, and said passages extend downwardly upon the outside of the conical mouth-piece *k*, and are curved or bent laterally and left open at their lower ends, as shown in Figs. 3 and 7. These passages or ducts are preferably V-shaped in cross-section in order to offer as little resistance to the water as possible; but it is apparent that their form, as well as the form in cross-section of the pounders themselves, may be varied without departing from the spirit of my invention. It is likewise obvious that the number of passages *q* may be varied. By reason of the manner of attaching the pounders to the shaft, they will at all times occupy an inclined position, as shown in Fig. 1, and as they are raised and lowered by the rotation of shaft *D* their lower ends move up and down against the lower inclined face of the cleats *a*.

As the pounders are raised, the air presses the disk *n* downward and fills the interior of the pounders; but as soon as the latter begin their downward motion the disk *n* will close the air-inlet *m*, and the air within the pounder will be forced through the passages *q* and discharged into the water from the lower ends thereof. By reason of the lower ends of the passages being bent or curved laterally, as shown, the water is prevented from being forced directly up into them as the pounders are reciprocated in a vertical plane.

The forcible discharge of air at the lower ends of the pounders assists in agitating the water and aids materially in the cleansing operation.

Having thus described my invention, what I claim is—

1. In combination with a compartment, as *B*, provided on two of its opposing faces with cleats *a' a'*, beveled, as shown, a cranked shaft, *D*, located directly above the compartment *B*, pounders *G G*, applied directly to said shaft, all substantially as shown, and means for imparting motion to shaft *D*, whereby the machine is adapted to be run backward or forward, as desired.

2. In combination with a compartment, as *B*, provided on two of its inner faces with beveled cleats *a' a'*, a cranked shaft, *D*, located di-

rectly above the compartment, pounders *G G*, depending from the cranks of the shaft, a gear-wheel, *E*, secured upon the end of shaft *D*, and a gear-wheel, *F*, mounted upon the tub to 65 mesh with wheel *E*.

3. In a washing-machine, the pounder *G*, comprising a hollow main body, *j*, having a perforated cap, *l*, an inwardly-opening valve, *n*, to close the perforation in the cap, and external air ducts or passages, *q*, communicating at their upper ends with the main body and open at their lower ends, the main body of the pounder being free from obstructions of any kind. 75

4. In a pounder for washing-machines, the combination, with the main body *j* and valve *n*, of the external air-ducts, *q*, communicating at their upper ends with the interior of the pounder and curved or bent laterally at their lower ends, which are open, all substantially as shown. 80

5. In combination with the hollow main body *j*, provided at its upper end with a threaded neck and with a cross-bar, *p*, a threaded cap, *l*, provided with an opening, *m*, a valve, *n*, adapted to close the opening, a spring, *o*, to hold the valve to its seat, and external air-ducts, *q*, communicating at their upper ends with the interior of the hollow body *j*, all substantially as shown. 85

6. The herein-described clothes-pounder, comprising a hollow body, *j*, provided with an inlet-valve at its upper end and with external air-ducts, *q*, communicating at their upper 95 ends with the interior of the hollow body.

7. In combination with the pounder *G*, having the hollow body *j*, conical mouth-piece *k*, and inlet-valve *n*, the external air-ducts, *q*, communicating at their upper ends with the hollow body and having their lower open ends bent or curved laterally upon the outside of the conical mouth-piece. 100

8. In a pounder for use in washing-machines, the combination, with a hollow body provided at its upper end with an inwardly-opening valve, of an external air-duct (one or more) communicating at its upper end with the interior of the hollow body, and having a lateral discharge-orifice, all substantially as shown. 105

9. In combination with a tub, a crank-shaft, and a pounder, a three-part block, as *H*, connecting the pounder to the shaft, and means for operating the shaft, all substantially as described. 110

In testimony whereof I affix my signature in presence of two witnesses.

NATHAN S. RUDDOCK.
